COMBINATION TRAY AND CONTAINER FOR AUTOMOBILES

Walter Brown, Cleveland, Ohio

Application February 4, 1959, Serial No. 54,455

Term of patent 14 years

(Cl. D14—6)

Fig. 1 is a perspective view of a combination tray and container for automobiles, embodying my new design; and

Fig. 2 is an elevational end view thereof.

I claim:

The ornamental design for a combination tray and container for automobiles, as shown.
